UNITED STATES PATENT OFFICE.

ADDISON VANDERVOORT, OF BELLEVILLE, CANADA.

LAWN-SPRINKLER.

SPECIFICATION forming part of Letters Patent No. 691,419, dated January 21, 1902.

Application filed March 8, 1901. Serial No. 50,360. (No model.)

To all whom it may concern:

Be it known that I, ADDISON VANDERVOORT, a subject of the King of Great Britain, residing at Belleville, in the Province of Ontario and Dominion of Canada, have invented a new and useful Lawn-Sprinkler, of which the following is a specification.

This invention relates to lawn-sprinklers; and the primary object of the invention is to 10 provide a simple, reliable, and efficient sprinkler which is self-regulating and adjusting and for that purpose provided with suitable actuating mechanism and gearing whereby the nozzle of the sprinkler is revolved or swung 15 through a horizontal orbit, as well as deflected from a vertical to a horizontal position, and vice versa. By this means the sprinkler is adapted to cover a large area of one hundred feet in diameter, more or less, thoroughly wetting and sprinkling the entire surface within 20 such area.

It is also an object of this invention to provide means for effectually regulating the speed at which the mechanism of the sprinkler is 25 actuated by providing a regulating device which governs the amount of water or size of the impact-stream which is utilized to impart rotary motion to the water-motor wheel from which the remaining parts of the lawn- 30 sprinkler are driven.

A further object of the invention is to provide a novel form of supporting-base for the lawn-sprinkler, which is adapted to be used in connection with a series of detachable brace- 35 arms, which can thus be removed when the machine is not in use to render the machine as a whole more compact for transportation and storage.

With the above and other objects in view, 40 the nature of which will more fully appear as the description proceeds, the invention consists in the novel construction, combination, and arrangement hereinafter fully described, illustrated, and claimed.

45 In the accompanying drawings, Figure 1 is a perspective view of a lawn-sprinkler constructed in accordance with the present invention. Fig. 2 is a side elevation of the same. Fig. 3 is also a view in elevation of 50 the sprinkler, taken at right angles to Fig. 2. Fig. 4 is a detail perspective view of the supporting-base, showing the tubular standard,

the supply-elbow, and the regulating device for the propelling-stream. Fig. 5 is a detail sectional view of the regulating device. Fig. 55 6 is an enlarged detail longitudinal section through the nozzle, showing the means for swiveling the pitman thereto. Fig. 7 is a detail perspective view of the bracket which is connected to the tubular standard and which 60 supports certain members of the gearing.

Like numerals of reference denote like parts in all the figures of the drawings.

In carrying out this invention I employ a supporting-base 1, which is in the form of a 65 flat disk, as best illustrated in Fig. 4, which base is provided with a tubular standard 2, extending upward therefrom and preferably arranged centrally thereof, said standard forming a part of the tubular connection with 70 the discharge-nozzle. Communicating with the lower end of the standard 2 is a supply-elbow 3, projecting at its outer end beyond the periphery of the supporting-base 1 and threaded, as at 4, to receive the coupling of 75 a suitable hose wherewith to supply water to the elbow 3 and tubular standard 4 preparatory to delivering the water to the nozzle hereinafter described.

The base 1 is provided with a series of peripheral notches 5, which are crossed by overlying and underlying arcuate straps 6, which, together with the notches, constitute a plurality of radially-disposed sockets for the reception of a corresponding series of detachable brace-arms, usually in the form of round wooden sticks. (Clearly shown in Fig. 1.) These brace-arms serve to provide a broad bearing for the sprinkler as a whole and effectually prevent the sprinkler from tipping 80 over under the action of the stream of water forced therefrom under pressure.

Surrounding the tubular standard 2 and journaled thereon is a water-motor wheel 7, comprising a cylindrical central portion 8, 85 with outwardly-extending parallel flanges 9, between which are secured a circular series of blades 10, having their outer extremities deflected rearwardly with respect to the direction of rotation of the wheel and adapted 90 to receive the impact of a stream of water which is delivered from an upstanding nipple 11, communicating with the supply-elbow 3 and preferably extending across within the

elbow 3, as shown in Fig. 5, where it is provided with an opening 12 to receive a portion of the inflowing supply of water. The upper end of the nipple 11 is internally screw-threaded to receive an externally-threaded regulating-tube 13, which is provided in one side with a longitudinal slot 14, forming the discharge-opening for the water passing through the nipple. The tube 13 is surrounded by a regulating cap or cut-off 15, which has a screw-threaded engagement therewith and which may be adjusted lengthwise of the tube 13 for closing the discharge-opening 14 to any desired extent for the purpose of regulating the size and strength of the impact-stream which acts upon the blades of the motor-wheel. The tube 13 is provided at its upper end with a milled head 16 to facilitate the turning thereof, so as to move the lower end of the slotted opening 14 below the upper extremity of the nipple, said expedient also serving as a means for regulating the size and strength of the stream which actuates the lower wheel. The upper end of the tube 13 is internally threaded to receive a threaded plug 17, which may be removed for the purpose of flushing out the tube 13 and freeing the same from any sediment which may accumulate therein.

In journaling the wheel 7 upon the tubular standard 2 said wheel is provided with a centrally-arranged upstanding sleeve 18, and said sleeve is encircled by a thread 19, forming a worm which meshes with the teeth of a nozzle-turning worm-wheel 20, the said worm-wheel being journalled upon a stud-axle 21, carried by the outwardly-projecting arm 22 of a ring or collar 23, which surrounds the tubular standard above the sleeve 18 of the motor-wheel and is held in place by means of a binding-screw 24, so as to prevent rotation thereof. Fixedly connected to the worm-wheel 20 is a driving-worm 25, and under the preferred embodiment of this portion of the invention the wheel 20 and worm 25 are rigidly mounted upon a sleeve 26, which is journalled on the stud-shaft 21, the arrangement being best illustrated in Fig. 3.

Superimposed above the motor-wheel 7 is a rotary disk 27, which is provided on its under side with a crown-gear 28, the teeth of which are engaged by the worm 25, as illustrated in Fig. 3. The disk 27 is provided with a central depending hub portion or collar 29, which is seated upon the ring or collar 23 and is adapted to rotate thereon. The disk 27 forms a support for an upstanding bracket 30, comprising parallel arms 31, which receive a crank-shaft 32, upon which is journalled a nozzle-deflecting worm-wheel 33, said wheel being interposed between the arms 31 and having its teeth in engagement with a worm-thread 34, formed on the outer surface of a tubular plug 35, constituting a detachable extension of the upper end of the standard, the said plug fitting tightly by friction into the upper end of the tubular standard

2, as best illustrated in Fig. 1. As the tubular standard 2 is non-rotatable, the tubular extension 35 thereof will also be held stationary and a rotary motion will be imparted to the wheel 33 by reason of the fact that said wheel is moved in a circular path around the standard, while its teeth always remain in engagement with the worm-thread 34.

The discharge-nozzle 36 is connected with the extension or plug 35 by means of a piece of flexible hose 37, and in this way the nozzle is flexibly connected to the tubular standard, so that the nozzle may be deflected from the vertical. The body 38 of the nozzle is provided with a fixed collar 39, and the removable portion of the nozzle 36 is also provided with a collar 40, while lying between said collars is a ring 41, which is provided at one side with a tangentially-disposed cross-head 42, upon the opposite ends of which are journaled a pair of sleeves 43, carried by the forked upper end of a pitman 44, the lower end of which is also forked and the arms 45 thereof provided with bearing-sleeves 46, which embrace the crank-pins 47 of a pair of cranks 47 at the opposite ends of the crank-shaft 32, upon which the nozzle-deflecting worm-wheel 33 is fixedly mounted.

From the foregoing description it will be understood that the motion imparted to the motor-wheel 7 by means of the propelling-stream from the nipple 11 is communicated to the disk 27 by means of the worm-thread 19, the worm-wheel 20, the driving-worm 25, and the crown-gear 28. The supporting-bracket 30 is thus caused to revolve around the tubular standard, and by reason of the specific connection between said bracket and the discharge-nozzle the nozzle is carried around through a circular path. As the nozzle-deflecting worm-wheel 33 revolves around the tubular standard the teeth thereof are engaged by the thread 34, and a comparatively slow rotary motion is imparted to the crank-shaft 32, thereby slightly revolving the cranks 47 and by means of the connecting-pitman 44 depressing or elevating the discharge-nozzle. It will thus be seen that the nozzle is simultaneously revolved and deflected and that both operations are automatically performed without any attention on the part of the operator and by the motion derived from the water-motor wheel 7. The speed at which the motor-wheel is driven is governed by the impact-stream, which may be regulated by the means described.

In the use of the sprinkler it is only necessary to set the sprinkler in the center of the area to be sprinkled and apply the supply-hose and brace-arms thereto. After adjusting the propelling-stream to give the required speed to the motor-wheel the device will operate automatically to sprinkle the entire area within the limits of the outer circle.

From the foregoing it is thought that the construction, operation, and many advantages of the herein described invention will

be apparent to those skilled in the art without further description, and it will be understood that various changes in the size, shape, proportion, and minor details of construction 5 may be resorted to without departing from the spirit or sacrificing any of the advantages of the invention.

Having thus described the invention, what I claim is—

10 1. In a lawn-sprinkler, the combination with a supporting-base, of a tubular standard, a rotatable nozzle resiliently connected with the standard, and a water-motor wheel journaled around the standard and operatively connect- 15 ed with the nozzle.

15 2. In a lawn-sprinkler, the combination with a supporting-base, of a tubular standard, a water-motor wheel journaled around the standard, a nozzle flexibly connected to the standard, and gearing actuated by the motor-wheel for swinging and deflecting the nozzle.

20 3. In a lawn-sprinkler, the combination with a supporting-base, of a tubular standard rising therefrom and provided at the bottom with

25 a supply-elbow, a discharge-nozzle flexibly connected to the tubular standard, and a water-motor wheel journaled around the standard and geared to the nozzle for automatically deflecting said nozzle.

30 4. In a lawn-sprinkler, the combination with a supporting-base, of a tubular standard, a water-motor wheel surrounding the standard, a disk journaled on the standard and geared to the motor-wheel, a nozzle flexibly connect- 35 ed to the standard, and gearing connecting said disk with the nozzle for swinging and deflecting the latter.

35 5. In a lawn-sprinkler, the combination with a supporting-base, of a tubular standard, a water-motor wheel provided with a central 40 sleeve loosely surrounding the standard, a disk journaled on the standard and geared to the motor-wheel sleeve, a nozzle flexibly connected to the standard, and gearing connect- 45 ing said disk with the nozzle for swinging and deflecting the latter.

40 6. In a lawn-sprinkler, the combination with a supporting-base, and a tubular standard thereon, of a water-motor wheel surrounding 50 the standard, a superimposed disk driven by the motor-wheel, a nozzle flexibly connected to the standard, and a gear-wheel driven by the standard and having a crank-and-pitman connection with the nozzle.

55 7. In a lawn-sprinkler, the combination with a supporting-base, and a tubular standard thereon, of a water-motor wheel surrounding the standard, a superimposed disk driven by the motor-wheel, a nozzle flexibly connected 60 to the standard, a worm fast on the standard, and a worm-wheel driven thereby and having a crank-and-pitman connection with the nozzle.

8. In a lawn-sprinkler, the combination with 65 a supporting-base and a tubular standard thereon, of a water-motor wheel surrounding the standard, a superimposed disk driven by

the motor-wheel, a tubular standard extension, a nozzle flexibly connected to said extension, a driving-worm on the extension, and 70 a worm-wheel driven thereby and having a crank-and-pitman connection with the nozzle.

9. In a lawn-sprinkler, the combination with a supporting-base, and a tubular standard thereon, of a water-motor wheel surrounding 75 the standard, a standard extension consisting of a hollow plug removably held in the upper end of the standard, a nozzle flexibly connected to said extension, and gearing interposed between the nozzle and motor-wheel for swing- 80 ing and deflecting the nozzle.

10. In a lawn-sprinkler, the combination with a supporting-base, and a tubular standard thereon, of a water-motor wheel surrounding the standard, a superimposed disk provided with a crown-gear operatively connect- 85 ed with and driven by the motor-wheel, a nozzle flexibly connected to the standard, and a gear-wheel driven by the standard and having a crank-and-pitman connection with the 90 nozzle.

11. In a lawn-sprinkler, the combination with a supporting-base, of a tubular standard, a water-motor wheel journaled around the standard, a nozzle flexibly connected to 95 the standard, a gear-wheel actuated by the motor-wheel, a pitman operatively connected with said wheel, and a swiveled collar on the nozzle provided with a cross-head to which said pitman is connected. 100

12. In a lawn-sprinkler, the combination with a supporting-base, and a tubular standard mounted thereon and provided with a supply-elbow, of a water-motor wheel journaled around said standard, a nozzle flexibly 105 connected to the standard, gearing between the motor-wheel and nozzle for deflecting and swinging the latter, and means for directing a propelling-stream against the motor-wheel, said means comprising a nipple connected 110 with and receiving its supply from the supply-elbow, a tube adjustably mounted in said nipple and provided with a discharge-opening, a threaded cap for partially closing said opening, and means to facilitate the turning 115 of said tube and cap, for the purpose specified.

13. In a lawn-sprinkler, a supporting-base provided with radially and horizontally disposed sockets, in combination with brace-arms detachably inserted in said sockets. 120

14. In a lawn-sprinkler, a supporting-base in the form of a flat disk provided with peripheral notches, and overlying and underlying arcuate straps crossing the notches and forming sockets for the reception of brace- 125 arms.

In testimony that I claim the foregoing as my own I have hereto affixed my signature in the presence of two witnesses.

ADDISON VANDERVOORT.
